UNITED STATES PATENT OFFICE.

PAUL DEHNE, OF HALLE, GERMANY.

PUMP-KETTLE.

No. 890,412.

Specification of Letters Patent.

Patented June 9, 1908.

Application filed September 11, 1907. Serial No. 392,403.

To all whom it may concern:

Be it known that I, PAUL DEHNE, subject of the Emperor of Germany, residing at Halle, Province of Saxony, Kingdom of Prussia, Empire of Germany, have invented certain new and useful Improvements in or Connected with Pump-Kettles, of which the following is a specification.

This invention relates to pump strainers and has for its object the production of a device of this class adapted to be fixed on the casing of the non-return valve of suction pipes, and one embodying an organization of parts that may be readily separated and associated and also altered or adjusted to modify the size and fineness of its apertures.

The preferred form of the invention is shown in the accompanying drawing, wherein:

Figure 1 is a longitudinal section of the improved pump strainer and the pipe carrying it. Fig. 2 is a detail plan view of one of the rings.

Similar characters of reference are employed to indicate corresponding parts in the views.

The pump strainer is composed of a series of separate rings *a* which are superimposed and held together and connected to the casing *c* of the non-return valve *h* by means of screws or coupling rods *b*, the inner annular valve chamber formed by the rings being covered on the side opposite the said valve *h* by a plate or disk *e* also fastened by the screws or coupling rods *b* and engaging or resting on the outermost ring *a*. The rings *a* are provided with projections or bosses *g* at intervals, as shown by Fig. 2, whereby the apertures *f*, necessary for the passage of the drawn up fluid, are formed. According to the essential feature of the invention, the rings *a* forming the suction strainer have uneven contiguous edges or faces providing the walls of the apertures or passages *f*, the said edges or faces as shown being of zigzag form. The advantage of this construction in view of pump strainers having straight slots between the rings is that long thin foreign bodies, such for instance as straw haulms, are prevented from being sucked into the strainer through the apertures or passages *f* and such bodies

are also much less liable to block or choke the apertures or passages *f* by reason of the zig-zag-shaped form of the apertures which will not admit of any material extent of the apertures or passages *f* being covered by thin strip-shaped bodies sucked thereagainst. The zigzag-contour of the contiguous edges or faces of the rings may be constructed to embody equivalent forms, such as rectangular, polygonal, or round shapes, or any analogous contour that will effect the production of an aperture or passageway having its continuity broken by interval projections.

The covering disk *e* is preferably given the conical form shown by Fig. 1, the point of the cone projecting into the interior of the pump strainer to facilitate guiding of the entering water or liquid to the valve opening *h'*. The projections *g* may also be provided on both faces instead of on only one face of each ring *a* and may be in one piece with the rings or formed as separate intermediary pieces. The latter arrangement is advantageous because with it the changing of the projections or intermediate separating devices or modifying the thickness thereof will result in a corresponding variation of the apertures or passages *f*.

What is claimed as new, is:

The combination with the non-return valve casing of suction pipes, of a covering disk, and a plurality of superimposed rings connected to one another and to the said valve casing, the rings forming in common with the covering disk the chamber of the pump strainer, and the said rings having opposite zigzag edges to form correspondingly shaped passages between their contiguous edges when assembled to form the wall of the strainer, the rings being displaceable with relation to each other within certain limits without producing circumferentially straight slots therebetween.

In testimony whereof I have hereunto set my hand in presence of two subscribing witnesses.

PAUL DEHNE.
